KITE REEL

Henry A. Wilson, 1000 Eldorado Ave.,
Clearwater Beach, Fla.

Filed Oct. 7, 1965, Ser. No. 87,365

Term of patent 14 years

(Cl. D41—1)

FIG. 1 is a perspective view of a kite reel showing my new design;

FIG. 2 is a side elevational view, and

FIG. 3 is the opposite side elevational view.

I claim:

The ornamental design for a kite reel, substantially as shown.
